BODY JACK

George M. Walraven, Kenosha, Wis., assignor to
Snap-On Tools Corporation, Kenosha, Wis., a
corporation of Delaware

Application August 13, 1938, Serial No. 224,835

6 Claims. (Cl. 254—98)

This invention relates to mechanical jacks and more particularly to automobile body jacks, although certain features thereof may be employed with equal advantage for other purposes.

5 It contemplates more especially the provision of an improved mechanical jack that is simple and compact in construction, provides for ratcheting actuation thereof and operation with minimum wear and effort in the effecting thereof.

10 One object of the present invention is to simplify the construction and improve the operation of devices of the character mentioned.

Another object is to provide an improved mechanical jack of simple and compact construction 15 that will operate with minimum wear and effort in the use thereof.

Still another object is to provide an improved body jack that is of durable and rugged construction to operate with minimum wear and effort.

20 A further object is to provide a simple and improved mechanical jack that is capable of sustaining ratchets without any appreciable wear on the acting elements.

A still further object is to provide improved 25 ratcheting devices in conjunction with a mechanical jack.

Still a further object is to provide an improved ratcheting actuator for a mechanical jack that has frictional means to provide for efficient 30 ratcheting operation.

Other objects and advantages will appear from the following description of an illustrative embodiment of the present invention.

In the drawings:

35 Figure 1 is a sectional view of a ratchet actuator for a mechanical jack taken substantially along line I—I of Figure 2.

Figure 2 is a plan view of a body jack embodying features of the present invention.

40 Figure 3 is a side view in elevation of a detachable member utilizable in conjunction with the jack shown in Figure 2.

Figure 4 is a sectional view taken substantially along line IV—IV of Figure 2.

45 Figure 5 is a fragmentary sectional view of an adaptor capable of use in conjunction with the jack extremities shown in Figure 2 that is substituted for the heads therein shown.

Figure 6 is a front view in elevation of a shank 50 for receiving different types of heads for detachable association with the ends of the jack shown in Figure 2.

Figure 7 is a side view in elevation of a modified form of adaptor for the ends of the jack shown 55 in Figure 2.

This provides for the connection of any suitable

Figure 8 is a perspective view of an actuator ratchet shown in conjunction with its pawl constituting a part of the ratcheting device utilized in connection with the mechanical jack shown in Figures 1 and 2.

5 Figure 9 is a fragmentary sectional view taken substantially along line IX—IX of Figure 1.

Figure 10 is a sectional view taken substantially along line X—X of Figure 9.

10 Figure 11 is a sectional view taken substantially along line XI—XI of Figure 9.

Figure 12 is a sectional view taken substantially along line XII—XII of Figure 9.

15 Figure 13 is a sectional view taken substantially along line XIII—XIII of Figure 9.

Figure 14 is a quarter section view in elevation of the end bumper head shown in Figure 2.

20 Figure 15 is a sectional view taken substantially along line XV—XV of Figure 14.

The structure selected for illustration comprises an elongated tubular cylindrical member 10 that telescopically receives a screw member 11 that is freely disposed therein and has an external diameter somewhat smaller than that of the external diameter of the tubular sleeve 10 to permit longitudinal movement without any lateral play or displacement.

Consequently, the screw member 11 will be freely displaceable within the tubular sleeve 10 which precludes any lateral movement therebetween to serve as a guide therefor.

The tubular sleeve 10 has an open extremity 12 to externally receive a correspondingly shaped shank 13 having spring impelled detents 14 and 15 mounted radially therein. The shank 13 has a flanged periphery 16 which engages the open extremity 12 of the tubular sleeve 10, and an extension 17 projects therefrom to receive any suitable type of end bumper 18 (Figures 2 and 14).

In order to preclude accidental removal between the bumper head 18 and the shank 17, the latter is provided with radially disposed spring impelled detents 19 and 20 that correspond in construction and mounting with the detents 14—15.

To this end, the bumper head 18 is of resilient material such as ebonite which is molded or otherwise shaped around a metallic base 21 terminating in a shank 22 having a polygonal bore 23 therein. The polygonal bore 23 may be provided with suitable depressions 24 which co-operate with the spring impelled detents 19—20 to retain the head 18 with its polygonal bore 23 in closely threaded connection with the correspondingly shaped and complementary polygonal shank extension 17.

This provides for the connection of any suitable

type of end bumper 18 to one end of the sleeve 10 through the medium of an adaptor shank 13 having vertical extension 17 formed thereon and suitably fitted with spring impelled detents 14-15 and 19-20. Should it be desired to provide any other type of end connected instrumentalities such as a hook 26 to the open end 12 of the sleeve 10, the latter may be provided with an integral shank 27 that fits into one end 12 of the tubular sleeve 10 or an adaptor may be interposed therebetween of suitable design to effect a detachable connection so as to avoid accidental separation therebetween.

15 A peripheral flange 28 may be formed intermediate the hook 26 and shank 27 and provided with a radial aperture 29 so as to afford the attachment of a spanner wrench thereto for establishing a detachable connection between the shank 27 and the tubular sleeve end 12. For that matter, adaptors may be interposed between the shank extension 17 and any other type of bumper head. One form may consist of a tubular member 30 (Figure 5) having depressions 31 formed in an internal polygonal bore 32 for detachable connection to the shank extension 17 having complementary detents 19-20 that cooperate with the depressions 31 in the polygonal bore 32. A slotted polygonal extension 33 may be formed on the tubular adaptor member 30, it 20 conforming to the tubular extension 17 and is provided with more spring impelled detents 34 and 35.

Another type of adaptor is shown in Figure 7 wherein the tubular base portion 36 terminates in a spherical shank 37 having spring impelled detents 38 and 39 extending therefrom. A depression 40 may be formed in the tubular base 36 to cooperate with any types of detents 19-20 depending upon the type and configuration of the 25 shank of any bumper end that may be available for detachable association with the open end 12 of the tubular sleeve. Various other types of bumper heads may be used depending upon the requirements of any particular work or which 30 may be differed within a wide range in connection with the body jack utilized to sustain indentations and irregularities resulting through accident and impact.

The other end of the tubular sleeve 10 terminates in a cylindrical reinforcing body 41 that has an axial bore 42 formed therein for a partial extent of its length to tightly receive a correspondingly sized extremity 43 of the tubular sleeve 10. A knurled handle rod 44 may be connected to the reinforcing sleeve body 41 through the medium of its flanged extremity 45 that engages correspondingly threaded aperture 46 provided radially through the sleeve body 41 to receive its axial bore 42. Consequently, the knurled 40 rod 44 can be switched to the aperture 46 so that its extremity 47 will frictionally engage the sleeve 10 to effect tight connection between the tubular sleeve 10 and its reinforcing body 41 so as to constitute a single element.

45 Another set screw 48 may be threaded through the aperture 49 on the reinforcing body 41 so as to engage the sleeve 10 (Figures 9 and 11) so as to cooperate with the rod handle 44 in effecting a fixed connection between the sleeve 10 and its 50 reinforcing body 41. Another set screw 50 is in threaded engagement with correspondingly threaded aperture 51, the set screw 50 having a reduced extremity 52 that projects in a key-groove 53 stamped or otherwise formed along the length of the screw member so as to preclude

relative rotation thereof with the sleeve 10 that are, however, axially displaceable relative to each other.

5 As shown, the screw member 11 terminates in a cylindrical extremity 54 that is preferably provided with spring impelled detents 55 and 56 to detachably receive the adaptor body 30 (Figures 2 and 5) or any other type to which can be connected the other end bumper 57. In order to displace the tubular sleeve 10 and screw member 11 inwardly or outwardly relative to each other, an improved ratcheting device 58 is provided. The ratcheting device 58 comprises a cast, forged or otherwise shaped body 60 which is suitably recessed to define a circular chamber 61 open on one side for the reception of a revolute member 62. The revolute member 62 is retained for journalled rotation within the chamber 61 of the body 60 by means of a face plate 63 which conforms in contour with the chamber 61 for attachment to the body 60 by means of suitable fasteners 64.

20 The fasteners 64, in this instance four, extend through the face place 63 for engagement with the body 60. The confronting external surfaces 21 of the chamber 61 defined by the body 60 and the face plate 63 are apertured to provide axially aligned bores 65 and 66, respectively, in communication with the interior chamber 61 thereof. As shown, the bore 65 is provided with a hardened bearing insert 67 that is pressed therein from the interior of the chamber 61 so that the enlarged peripheral rim 68 thereon will abut against the correspondingly shaped peripheral shoulder 69 provided in the body 60 adjacent and in communication with the bore 65. The bearing insert 67 is of a high quality alloy steel that is hardened to sustain unusually heavy loads for extended periods without appreciable wear thereon. The plate 63 is also of a high quality alloy 30 steel that is hardened to correspond in durability with the hardened insert 67 so that its bore 16 will assist in conjunction with the hardened insert 67 in rotatively supporting the revolute member 62 having axially extending hubs 69 and 40 70 journalled thereon.

45 In order to impart rotation to the revolute member 62 responsive to oscillatory movement of the body 60, the periphery thereof is provided with radially extending ratchet teeth 71 cut or otherwise formed for extension therefrom. As shown, a circular recess 72 is provided in the body 60 to communicate with the chamber 61, it being in longitudinal alignment therewith to receive a correspondingly shaped circular pawl 73 5 journalled for rotation therein with the periphery thereof partially disposed in the chamber 61. To this end, the pawl 73 has integral axial aligned hubs 74 and 75 received in correspondingly shaped bores 76 and 77 provided in the body 60 and closure plate 63.

50 A lever 78 having a polygonal stem 79 is disposed for reception in a somewhat larger and correspondingly shaped polygonal recess provided axially within the pawl hub 74 to establish fixed 5 connection therewith by means of a threaded stud 80, constitutes a manual rotary adjustment for the pawl 73. To enable ratcheting of the revolute member 62 in opposed directions by rotary adjustment of the lever 78 to its "out" or "in" positions designated on the body 60, the pawl 73 has the periphery thereof interrupted to define confronting pawl teeth 81 and 82.

55 The pawl teeth 81 and 82 are complementary to the ratchet teeth 71 for independent meshing.

engagement therewith depending upon the rotary position of the pawl 73 which is adjusted by the lever 78 to control the directional rotation of the revolute member or ratchet wheel 62. The pawl teeth 81 and 82 are sufficiently spaced so that one or the other will be in operative engagement with a ratchet tooth 71 to enable the desired rotary throw of the head 60 for ratcheting purposes without interference with the inactive pawl tooth. During the ratcheting action, the pawl 73 partially rotates about its axis until the next successive ratchet tooth 71 is engaged by the active pawl tooth 81 or 82 depending upon the direction of the ratcheting action. It will be observed that this construction provides hardened bearings 66 and 67 for the revolute member 62 and that the pawl 73 is supported by the axial hubs 74 and 75 on both sides thereof with the plate 63 providing a hardened bearing therefor to sustain a load thereon.

To maintain the pawl 73 stationary and in adjusted positions for the desired directional ratcheting, a positioning ball or detent 83 is resiliently mounted on a spring 84 confined in a passage 85 provided longitudinally in the body 60 for radial communication with the pawl receiving recess 72. The spring 84 urges the positioning ball 83 in the direction of the pawl 73 for engagement with the periphery thereof. To this end, the periphery of the pawl 73 is provided with conical cavities 86 and 87 for reception of the resiliently mounted positioning ball or detent 83. The cavities 86 and 87 are spaced for selective registry with the detent 83 to hold the pawl teeth 81 and 82, respectively, in meshing engagement with the teeth 71 of the revolute member 62, thereby enabling its rotation in a counterclockwise and clockwise direction (viewed from Figure 10) responsive to ratcheting or oscillating a handle 88.

The handle 88 is, in this instance, formed integral with the body 60. With the arrangement of parts above described, any suitable device for turning may be detachably or otherwise associated with the revolute member 62; however, in this instance the revolute member 62 is provided with an axial bore 89 that has square threads 90 cut therein to serve as a complement of and mesh with threads on the elongated member 11 so that rotation of the revolute member 62 in one direction will respectively effect the outer and inner relative displacement between the members 10-11 corresponding with the positioning of the pawl lever 78 in its out or in position (Figure 1).

It will be observed that the body 60 has a lateral peripheral flange 91 formed thereon to telescopically receive the tubular sleeve body 41 therein. To effect their connection and permit relative rotation between the ratcheting body flange 91 and the tubular sleeve body 41, an annular groove 92 is formed proximate to the extremity of the tubular sleeve body 41 so as to cooperate with the reduced extremities 93 and 94 of set screws 95 and 96, respectively, which project through correspondingly threaded apertures provided in the ratcheting body flange 91 (Figures 9 and 12). A ball bearing raceway 98 is confined in a casing 99 disposed and confined in a countersunk bore 100 provided axially in an open end tubular sleeve body 41 for contact therewith and the surface of the revolute member 62. It will be observed, therefore, that the ball bearing raceway 98 rests on the hardened bearing insert 67 that is pressed therein so that it will

withstand heavy loads with minimum wear thereon.

Consequently, relative rotation is possible between the ratcheting body 60 and the tubular body 41 while axial displacement is precluded therebetween so that the revolute member 62 will always exert a displacing effort upon the screw member 11 relative to the tubular sleeve 10 and its reinforcing body 41. A comparatively small opening 97 is preferably provided in the end of the ratcheting body 60 for communication with the chamber 61 for lubrication purposes. In order to preclude relative rotation between the tubular sleeve 10 and the screw member while the ratcheting device is being oscillated to procure another bite on the pawl 71 of the revolute member 62, a friction shoe 101 is reciprocally mounted in a radial opening 102 formed on a radial extension 103 of the revolute member 62.

The friction shoe 101 has a reduced portion 104 which presents a shoulder thereon to limit the initial movement thereof. The radial bore 102 is correspondingly shaped and communicates with the interior of the revolute member 62 so that the friction shoe end surface 105 will contact with the threads of the screw member 11. A split ring 106 embraces an annular groove 107 that is formed on the exterior surface of the friction shoe 101 for lodgement in a correspondingly shaped groove 108 formed on the interior of the revolute extension member 103.

Consequently, the split ring 106 serves as a resilient spring that urges and retains the friction shoe 101 in contact with the screw member 11 to preclude any idling relative movement therebetween. This enables the ratcheting displacement of the screw member 11 relative to the tubular sleeve 10 even though no urge is spread thereon. Otherwise there would be a tendency of the screw member 11 oscillating with the revolute member 62 which reduces their coacting and retards the efficient operation of the devices prior to actually constituting a ratchet. It will be observed, therefore, that the relative rotation between the revolute member 62 and the tubular sleeve body 41, is rendered possible with minimum wear and frictional reaction in spite of heavy loadings that may be exerted on the confronting surfaces thereof.

With the arrangement of parts above described, it should be noted that the ball bearing raceway 98 rests on the hardened bearing insert 67 that is pressed therein so that it will withstand heavy loads with minimum wear thereon. Should wear result after extended use then it will only be necessary to replace the bearing insert 67 for the ratchet device will practically be in its original mechanical condition by the provision of lubrication expedients and the bearing inserts and runways that sustain a load and participate in the movement between the relatively rotating parts. This accounts for the improved results and more efficient operation and an improved mechanical body jack that is compact as well as simple in construction.

Various changes may be made in the embodiment of the invention herein specifically described without departing from the invention or sacrificing any of the advantages thereof, and nothing herein shall be construed as limitations of the invention, its structural concept or embodiment as to the whole or any part thereof except as defined in the appended claims.

I claim:

1. In a portable mechanical jack, the combination with an elongated tubular sleeve, of an enlarged cylindrical body member telescopically associated with said tubular sleeve, a screw member telescopically associated with said sleeve and cylindrical body member for displacement relative thereto there being a concentric annular counter-groove in said body member, a revolvable ratchet wheel in screw meshing engagement with said screw member, a handle member having a swivel connection with said cylindrical body member, a reversible pawl carried by said handle member for engagement with said ratchet wheel, a ball bearing raceway confined in said annular counter-groove between said ratchet wheel and said cylindrical body, means for reversing the position of said pawl, and means for frictionally holding said ratchet wheel against displacement relative to said screw member unless responsive to pawl engagement with said ratchet wheel.
2. In a portable mechanical jack, the combination with an elongated tubular sleeve constituting the fixed end thereof, of an enlarged cylindrical body member fixed over the end of said tubular sleeve, a screw member telescopically associated with said sleeve and body member for displacement relative thereto, a revolvable ratchet wheel in screw meshing engagement with said screw member and resting against said body member, a handle member having a swivel connection with said body member, a ball bearing raceway interposed between said ratchet wheel and said body member to sustain the load and permit free turning therebetween, a reversible pawl carried by said handle member for engagement with said ratchet wheel, means for reversing the position of said pawl, there being a longitudinal slot that interrupts the surface of said screw member, means extending from said body member into said longitudinal slot to prevent relative rotation between said sleeve and body member and screw member, and means interposed between said ratchet wheel and screw member for frictionally holding said ratchet wheel against displacement relative to said screw member unless responsive to pawl engagement with said ratchet wheel.
3. In a portable mechanical jack, the combination with an elongated tubular sleeve constituting the fixed end thereof, of an enlarged cylindrical body member fixed over the end of said tubular sleeve, a screw member telescopically associated with said sleeve and body member for displacement relative thereto, a revolvable ratchet wheel in screw meshing engagement with said screw member and resting against said body member, a handle member having a swivel connection with said body member, a ball bearing raceway interposed between said ratchet wheel and body member to sustain the load and permit free turning therebetween, a reversible pawl carried by said handle member for engagement with said ratchet wheel, there being a longitudinal slot that interrupts the surface of said screw member, means extending from said body member into said longitudinal slot to prevent relative rotation between said sleeve and body mem-
- ber and screw member, a shoe in contact with said screw member, and spring means exerting an urge on said shoe for frictionally holding said ratchet wheel against displacement relative to said screw member unless responsive to pawl engagement with said ratchet wheel.
4. In a portable mechanical jack, the combination with an elongated tubular sleeve, of a screw member telescopically associated with said sleeve for displacement relative thereto, a revolvable ratchet wheel in screw meshing engagement with said screw member, a handle member having a swivel connection with said tubular sleeve, a ball bearing raceway interposed between said ratchet wheel and tubular sleeve to sustain the load and permit free turning therebetween, a reversible pawl carried by said handle member for engagement with said ratchet wheel, a shoe reciprocally mounted in said revolvable ratchet wheel, and split ring means embracing said revolvable ratchet wheel in the path of said shoe for frictionally holding said ratchet wheel against displacement relative to said screw member unless responsive to pawl engagement with said ratchet wheel.
5. In a portable mechanical jack, the combination with an elongated tubular sleeve, of a screw member telescopically associated with said sleeve for displacement relative thereto, a revolvable ratchet wheel in screw meshing engagement with said screw member, a handle member having a swivel connection with said tubular sleeve, a ball bearing raceway interposed between said ratchet wheel and sleeve to sustain the load and permit free turning therebetween, a reversible pawl carried by said handle member for engagement with said ratchet wheel, a shoe reciprocally mounted in said revolvable ratchet wheel, split ring means embracing said revolvable ratchet wheel in the path of said shoe for frictionally holding said ratchet wheel against displacement relative to said screw member unless responsive to pawl engagement with said ratchet wheel, and means extending from the ends of said tubular sleeve and screw member for engaging spaced parts to be spread or drawn toward each other.
6. In a portable mechanical jack, the combination with an elongated tubular sleeve, of a screw member telescopically associated with said sleeve for displacement relative thereto, a revolvable ratchet wheel in screw meshing engagement with said screw member, a handle member having a swivel connection with said tubular sleeve, a ball bearing raceway interposed between said ratchet wheel and tubular sleeve to sustain the load and permit free turning therebetween, a reversible pawl carried by said handle member for engagement with said ratchet wheel, a shoe reciprocally mounted in said revolvable ratchet wheel, springing means embracing said revolvable ratchet wheel in the path of said shoe for frictionally holding said ratchet wheel against displacement relative to said screw member unless responsive to pawl engagement with said ratchet wheel, and means interposed between said tubular sleeve and screw member to preclude relative rotation and permit longitudinal displacement therebetween.

GEORGE M. WALRAVEN.
